[57] CLAIM

The ornamental design for a jewelry, trinket and accessory organizer, as shown and described.

DESCRIPTION

FIG. 1 is a front elevational view of a jewelry, trinket and accessory organizer showing my new design;

FIG. 2 is a right side elevational view thereof, the left side being a mirror image of that shown;

FIG. 3 is a rear elevational view thereof; and

FIG. 4 is an enlarged top, front, and left side perspective view thereof.

FIG. 1

FIG. 2

FIG. 3
